UNITED STATES PATENT OFFICE

ERNEST VERITY, OF FREEPORT, NEW YORK

DESIGN FOR A COMBINED ASH TRAY, CARD, CIGARETTE, AND PENCIL HOLDER

Application filed January 3, 1933. Serial No. 46,693. Term of patent 14 years.

To all whom it may concern:

Be it known that I, ERNEST VERITY, a citizen of the United States, residing at Freeport, in the county of Nassau and State of New York, have invented a new, original and ornamental Design for a Combined Ash Tray, Card, Cigarette, and Pencil Holder, of which the following is a specification, reference being had to the accompanying drawing, forming part thereof.

The figure is a perspective view of the combined ash tray, card, cigarette and pencil holder, showing my new design.

I claim:

The ornamental design for a combined ash tray, card, cigarette and pencil holder as shown.

ERNEST VERITY.
